(57) CLAIM

The ornamental design for a manual vegetable cutter, as shown and described.

DESCRIPTION

FIG. 1 is a perspective view of a manual vegetable cutter showing my new design;

FIG. 2 is a plan view of the top of the manual vegetable cutter of the invention;

FIG. 3 is a plan view of the bottom of the manual vegetable cutter of the invention;

FIG. 4 is a plan view of the left side of the manual vegetable cutter of the invention;

FIG. 5 is a plan view of the right side of the manual vegetable cutter of the invention;

FIG. 6 is a plan view of the front of the manual vegetable cutter of the invention; and,

FIG. 7 is a plan view of the back of the manual vegetable cutter of the invention.

The broken lines are for illustrative purposes only and form no part of the claimed design.
